UNITED STATES PATENT OFFICE.

ALBERT MORLEY, OF CHICAGO, ILLINOIS, ASSIGNOR TO THE LASKEY COMPANY, OF SAME PLACE.

SEWING-MACHINE.

SPECIFICATION forming part of Letters Patent No. 499,845, dated June 20, 1893.

Application filed February 8, 1891. Serial No. 380,030. (No model.)

To all whom it may concern:

Be it known that I, ALBERT MORLEY, a citizen of the United States, residing at Chicago, in the county of Cook and State of Illinois, have invented certain new and useful Improvements in Sewing-Machines, which are fully set forth in the following specification, reference being had to the accompanying drawings, in which—

10 Figures 1, 2 and 3 represent a front elevation of a sewing machine head, embodying my invention, showing the devices for raising and lowering the needle-bar and presser-foot in different positions; Fig. 4, a detail section, 15 taken on the line 4, 4, of Fig. 1; Fig. 5, a detail plan section, taken on the line 5, 5, of Fig. 4; Fig. 6, a detail section, taken on the line 6, 6, of Fig. 4, looking from the rear; Fig. 7, a plan view of the presser-foot, detached; Fig. 20 8, a section of the same, taken on the line 8, 8, of Fig. 7; Fig. 9, a front elevation of the same; Fig. 10, a detail plan section, taken on the line 10, 10, of Fig. 4; Fig. 11, a plan of the machine bed, broken away, except at the 25 front; Fig. 12, a bottom plan view of the same and the feed mechanism mounted; and Fig. 13, a detail section, taken on the line 13, 13, of Fig. 11, with the addition of the presser-foot and needle.

30 My invention relates to presser-foot mechanism for sewing machines, the object being to provide a presser-foot which will yield horizontally backward to inequalities in the cloth, so that the latter will remain smooth.

35 I will proceed to describe in detail the construction and operation of a sewing machine embodying my invention in one practical way, so far as is necessary for an understanding of the present improvements, and will then 40 point out more definitely in claims the particular improvements which I believe to be new and wish to secure by Letters Patent.

All the main parts of the machine may be 45 of any ordinary construction and such of these parts as are shown in the drawings are of known form and type and will require no special description here.

In the drawings, A represents the bed of the machine, and B, the goose-neck or over- 50 hanging-arm and, C, the main shaft mounted in said arm. The needle-bar, D, is mounted

in the head, b, of the overhanging-arm, carries the usual needle, d, and is driven from the main shaft by any usual device. The presser-foot bar, E, is also mounted in the head b by the side of the needle-bar, passing loosely through cross-heads or blocks, b', at the top and bottom of the head b and free to slide up and down therein. A bracket, F, is fastened to the lower end of the presser-foot bar, the bracket being angular and the bar socketed in its vertical member, f. The horizontal member f' of this bracket is provided with a socket or recess, f'', opening out toward the needle-bar. The presser-foot, G, is made a separate piece and is mounted in the socket f'' of the bracket, being provided with an upright shank, g, which, at its upper end, is bent at right angles, so as to provide a short arm, g', which is adapted to enter the said socket, as seen in Fig. 8 of the drawings. A pin, G', is secured to the short arm of the presser-foot and extends thence through the presser-foot socket out at the rear end of the arm f', being provided with a head on the outside to stop its sliding movement in the opening through which it passes. A spring, g'', is arranged around this pin within the socket between the end of the arm g' and the bottom of the socket, which spring operates 80 to push the presser-foot outward, but yields readily to permit the latter to move backward upon slight pressure. The arm f' is also provided with a short slot, f', below the bent end or knee of the presser-foot, to permit the latter to move backward, as just described, and to prevent the shank thereof from rotating in its socket. Preferably the arm f' is also slightly inclined upward from front to rear, thereby giving the presser-foot a slight lift 85 whenever it yields backward in its socket. A collar, e, is fastened to the presser-foot bar somewhere near the middle of its length and above it is a spring, E', arranged around the bar between this collar and the upper block b', which spring serves to hold the presser-bar and foot down in proper working position under normal conditions. The collar e is also provided with a lug, e', projecting out at one side of the head and below this projection an ordinary lifting lever, e'', is pivoted to the head 90 and provided with a cam, e', adapted to act

upon the collar projection, so that the attendant may lift the bar at any time desired.

In the operation of the machine, the required lifting of this bar is obtained by special devices. A collar, H, is arranged upon the presser-foot bar a little below the fixed collar. This latter collar is loose on the bar, so as to move lengthwise thereof and between it and the fixed collar is a light spring, h, arranged around the bar, which affords a certain resistance to the upward movement of the sliding collar. A cam, I, is fastened to the front end of the main shaft and is provided with a cam groove, i, cut in its front face. As shown in the drawings this cam is a disk and is fastened to the main shaft by a pin, i', passing through the cam near its outer edge at some one point and secured to the crank-wheel, c, on the end of the shaft. In this instance, this fastening pin also constitutes the crank-pin, by means of which the needle is reciprocated. A link rod, h', connects the collar H to a lever, h², which is pivoted at its outer end to the head and extends inward in a nearly horizontal direction, being provided at its inner end with a pin, h³, which is fitted to the cam groove i and is, preferably, provided with an anti-friction roller running in the groove. The rotation of the cam I will lift and depress the presser-foot and its bar through the medium of the horizontal lever and its connecting rod running to the collar H, the cam groove being shaped to give the movements required. It will be noticed that the collar H is connected to the presser foot bar by a yielding device, so that all of its movements are yielding and injury to any of these parts is practically impossible under all conditions. It will be seen too that the presser-foot and its bar will yield upward bodily independently of the lifting collar H, by means of which it is raised and that the action of the latter is first to compress the spring above it until its resistance is greater than the resistance of the bar to upward movement, when, of course, the whole device moves upward. The cam groove i is a circle most of the distance around the cam, but at one side there is a section, i², nearly straight, preferably curving inward toward the center of the cam, as seen in Fig. 1 of the drawings.

In the bed A is fitted the usual throat-plate, a.

The feed devices are somewhat different from any in ordinary use.

Underneath the bed is the usual feed rock-shaft, K, provided at its front end with a crank, k. The feed bar, L, is fastened at one end to this crank, as usual, but at its other end is connected to a lug, M, depending from the bed and provided with a pin, m, which enters a short longitudinal slot, l, in the feed bar. This construction permits the reciprocation of the feed bar, as usual, but it will be seen that the slotted end has no vertical movement and the only vertical movement of the feed bar will be a slight vibration upon

the pin at this slotted end, due to the short oscillations of the crank to which the other end is fastened, as it turns from the position shown in Fig. 13, slightly forward toward the throat-plate and then back again in the usual manner. The feed bar carries an ordinary feed-plate, N, fastened to it and arranged to move within the usual slot within the throat-plate.

The operation of these devices is as follows: The devices which lift the presser-foot are organized, so that while the pin of the lifting lever is in the circular portion of the cam groove, the presser-foot will be in its lowest position and rest upon the fabric. The feed plate has the ordinary reciprocating movement timed, as usual, with reference to the movement of the needle, the only change being that the feed plate is moved substantially in a horizontal plane. Now when the feed plate commences its feeding movement, the fabric will be held between it and the presser-foot; but the latter being yielding in the direction of the feed, will move back with the plate, especially if there are any inequalities in the fabric, so that all wrinkling of the latter is effectually prevented; this position is shown in Fig. 2 of the drawings, where the needle is just passing down through the fabric. Just at this point the presser-foot is lifted bodily, owing to the bend in the cam groove, which operates the lifting lever which enters the cam groove at this point, as seen in Fig. 2. The presser-foot being thus relieved from all friction will at once spring forward to its normal position under the influence of its spring; this occurs while the pin of the lifting lever travels in the short irregular curve of the cam groove, but the moment it leaves this section and again enters the regular circle of the groove, the presser-bar descends under the influence of its spring and drops the presser-foot upon the fabric again, as will be seen from a study of Fig. 3, in which the position of the parts is shown just as the lever is at the end of the short curve of the cam groove. It will be seen from this figure that the presser-foot has been thrown forward again into its ordinary position and is just ready to drop upon the fabric; the needle at this point is still in the cloth, but is just on the point of being withdrawn and about at this point the feed plate makes its back movement, so that the fabric is again clamped between the presser-foot and feed plate, which then move forward together again, as described, to make the required feed, the presser-foot yielding in the direction of the feed as occasion may demand during this movement. It will also be seen from the description above that the presser-bar is free to yield upward at any time during its depressed position, owing to the fact that the collar, by which it is lifted bodily, is loose thereon, as already described. If, therefore, any obstruction passes under the toe of the presser-foot, the latter yields upward with the

bar to prevent breakage and they may be lifted by the attendant at any time, by means of the lifting lever, whenever desired.

In particulars of construction, I do not wish 5 to be understood as limiting my invention to precise details as herein described and shown, for changes may be made in these features without losing my principal improvements.

Having thus described my invention, what 10 I claim as new, and desire to secure by Letters Patent, is—

1. In a sewing machine, the combination, with a presser-bar, provided at its lower end with a substantially horizontal socket, of an 15 independent presser-foot, having its shank bent to fit and slide in said socket, a spring arranged in said socket and bearing against the shank to thrust the same normally forward toward the needle, means for preventing 20 said forward motion and means for preventing rotation of the shank in the socket, substantially as described.

2. In a sewing machine, the presser-bar, in

combination with the bracket F, provided with a substantially horizontal socket f^2 , the 25 presser-foot G, provided with a bent shank g, adapted to enter said socket, the pin G', and the spring g², substantially as and for the purposes specified.

3. The presser-foot bar E, in combination 30 with the collar e fixed thereon, the springs E' and h, the collar H loose on the bar, and lifting devices connected to said loose collar, substantially as and for the purposes specified.

4. The presser-foot bar, in combination with 35 the collar H loose and collar e fixed thereon, the lifting lever h², the link-rod h' connecting the loose collar to said lever, the springs E' and h and the revolving cam I, provided with a cam groove i constructed and arranged 40 to actuate the said lifting lever, as described, substantially as and for the purposes specified.

ALBERT MORLEY.
